(**) Term: **14 Years**

(57) **CLAIM**

The ornamental design for a door bell button mounted in golf ball, as shown and described.

(21) Appl. No.: **29/486,894**

DESCRIPTION

(22) Filed: **Apr. 10, 2014**

FIG. 1 is a front perspective view of a door bell button mounted in golf ball of my invention in use;

(51) LOC (10) Cl. **10-05**

FIG. 2 is a top plan view of a door bell button mounted in golf ball of my invention based on FIG. 1;

(52) U.S. Cl.

FIG. 3 is a bottom plan view of a door bell button mounted in golf ball of my invention based on FIG. 2;

USPC **D10/118.2**

FIG. 4 is a side view of a door bell button mounted in golf ball of my invention based on FIG. 1;

(58) **Field of Classification Search**

FIG. 5 reverse view of FIG. 4;

USPC D10/118.1, 118.2; D14/159; D13/158

FIG. 6 is a front plan view of a door bell button mounted in golf ball of my invention based on FIG. 1; and,

CPC H04M 11/02; H04M 11/025; H40N 7/186

FIG. 7 is a rear plan view of a door bell button mounted in golf ball of my invention based on FIG. 6.

See application file for complete search history.

The broken line showing of a hand and mounting plate is
